ADJUSTABLE ORIFICE VALVE

Loyd F. Defenbaugh, Oklahoma City, Okla.,
assignor to Phillips Petroleum Company, Bar-
tlesville, Okla., a corporation of Delaware

Application July 22, 1931, Serial No. 552,459

1 Claim. (Cl. 251—167)

My invention relates to flow control apparatus and more particularly to a device of that character commonly known as a "flow bean" for choking and adjustably controlling the flow of oil and 5 gas from wells.

The process of bringing in wells under high gas pressures, particularly in territories where a large amount of sand is present in the well fluid, is accompanied with the grave danger of sand cutting the master gates and other fittings usually employed for controlling wells.

It has also become necessary to restrict the flow of wells to a predetermined proportion of their entire output in order to comply with certain proration requirements.

The principal objects of my invention, therefore, are to provide a device for restricting the flow of well fluid to reduce its velocity and consequently decrease the sand-carrying power of the oil and gas issuing from the well; to embody means for reducing to a minimum the cutting action of the sand carried in the well fluid; and to provide means for readily adjusting the amount of restriction placed on the fluid so that the proper proportion thereof may be delivered from the well.

In accomplishing these and other objects of my invention I have provided improved details of structure, the preferred form of which is illustrated in the accompanying drawing, wherein:

Fig. 1 is a central longitudinal section of the control device shown in closed condition.

Fig. 2 is a perspective view of the valve parts in disassembled relation with a nipple shown partly in section to more clearly disclose its construction.

Fig. 3 is a cross section on the line 3—3, Fig. 1. Referring more in detail to the drawing:

1 designates the upper end of a conduit such 40 as well tubing projecting above a well hole, and preferably comprises the inlet for the apparatus although it would also serve as an outlet.

The upper end of the conduit is provided with 45 external threads 2 for engaging the internally threaded neck 3 of a T-fitting 4 having aligning, internally-threaded, opposite open ends 5 and 6. Secured in the open end 5 is a nipple 7 which may be provided with external threads 8 for connecting the device to an outlet conduit 9. The longitudinal opening of the nipple comprises oppositely directed conical portions 10 and 11 meeting at the approximate center of the nipple in a constricted bore 12, and the outer end of the portion 11 terminates in a more abruptly diverging 55 wall 13.

Snugly engaging the wall portion 11 is a valve seat member 14 having an outer face complementary to the wall 11, and including a linear, cylindrical, bore 15. Each of the ends of the seat member are tapered outwardly as shown at 5 16 and 17 respectively.

Slidably mounted in the opening 15 of the seat member is a valve plug 18 having a head 19 provided with a forwardly tapered surface 20 complementary to the tapered end 17 of the seat member to cooperate therewith, and terminating in a frusto-conical body portion 21 provided with grooves 22 increasing toward the forward end of the body both in width and depth.

It will be obvious that the grooves constitute 15 ports in connection with the seat member for communicating the inlet conduit with the outlet 9, and that by moving the valve body outwardly from its seat these ports will be gradually increased in size to permit the passage of a correspondingly greater amount of fluid through the 20 housing.

Means for moving the valve plug to open or closed position includes a valve stem 23 preferably anchored to the valve body by a threaded pin 25 24 engaging an internally threaded socket 25 of the body and secured in assembled condition therewith by a pin 26 extending transversely through aligning openings 27 and 28 in the pin 30 and body respectively.

A guide and sealing member 29 for the valve stem includes a head 30 engaging the internally threaded end 6 of the T-fitting, and is provided with a longitudinal guide opening 32 for slidably and rotatably receiving the valve stem 23. The 35 sealing member 29 is provided on its end with the screwthreaded portion 40 on which is secured the ring-shaped portion 41 of the member 31. Integrally formed arms or ribs 42 extend from the ring portion 41 and carry a boss 43 at 40 their outer ends which boss is internally threaded, as at 33, for receiving a threaded portion 34 of the valve stem, and packing material 35 in a socket 36 of the guide is urged into sealing 45 engagement with the stem by a gland 37 provided in the reduced portion in accordance with common practice.

The usual wheel 38 is anchored to the extreme outer end of the valve stem by a nut 39 for 50 rotating the stem to move the valve member axially to and from its seat.

Assuming a valve to be constructed and assembled as described, and to be mounted on the outlet end of well tubing, the operation for control- 55

ling the flow of fluid from a well would be as follows:

Since the grooves do not extend throughout the entire length of the plug portion, the valve member, when in fully seated condition, serves as a gate valve for preventing any flow of fluid from the well, but as soon as the valve member has been slightly moved from its seat to expose a portion of the V-shaped grooves 22, flow of fluid from the well immediately results.

Due to the gradually increasing width and depth of the grooves it will be apparent that the sand, after once entering the grooves upon sufficient opening of the valve, will pass freely into the outlet without any restrictions, and cannot therefore impart a serious cutting action on the valve. Consequently the life of a valve of this character is much prolonged over the usual devices provided for this purpose, which, due to their form are more subjected to the cutting action of sand and other abrasive ingredients carried in the oil.

If, however, after an extended period of service, the valve plug and seat member should become worn it is necessary only to replace these two members in order to obtain a fully reconditioned valve.

The valve plug, when in service, is never entirely withdrawn from the seat member but is supported by said member which prevents chattering and possible breakage of the stem.

While my invention has been described as being adapted particularly for controlling oil wells it will be apparent that this device will also serve satisfactorily as a valve for other purposes.

What I claim and desire to secure by Letters Patent is:

A flow controlled valve of the type described, comprising a casing having an inlet and an outlet, a nipple cooperating with said outlet and having a Venturi-shaped bore consisting of oppositely flared portions, one of said portions being positioned adjacent to said inlet, a choke collar arranged in the last mentioned portion of the bore and having a periphery conforming in shape to that portion of the bore, said collar having a bevelled valve seat at its inner end and provided with a substantially cylindrical bore, a valve head cooperating with said nipple and choke collar to restrict the flow of fluid therethrough, and provided with a tapered portion from which projects a substantially frusto-conical portion, the tapered portion of the valve head conforming to the tapered valve seat and being of greater diameter than the smallest internal diameter of the nipple, and means for moving the valve head toward and away from said choke collar and nipple.

LOYD F. DEFENBAUGH.
